UNITED STATES PATENT OFFICE.

JOHN A. DONNELLY, OF NEW YORK, N. Y.

TRAVERSE-CORD FASTENER.

1,215,126.

Specification of Letters Patent. Patented Feb. 6, 1917.

Application filed July 22, 1916. Serial No. 110,665.

To all whom it may concern:

Be it known that I, JOHN A. DONNELLY, a citizen of the United States, and a resident of the city of New York, borough of Manhattan, in the county and State of New York, have invented a new and Improved 5 Traverse-Cord Fastener, of which the following is a full, clear, and exact description.

This invention relates to supporting devices for portières, curtains or the like and has particular reference to means for attaching a traverse cord to the traverse rings of the drapery of the character indicated.

Among the objects of the invention, therefore, is to provide a novel form of traverse ring or cord attachment for traverse rings enabling the traverse cord to be attached directly to the traverse rings by any member 15 of the household, whether skilled or unskilled in this particular art.

A further object of the invention is to provide an attachment means for the traverse cord whereby the attachment of the traverse cord with the traverse rings will be facilitated and the appearance of the drapery will be materially enhanced.

With the foregoing and other objects in view the invention consists in the arrangement and combination of parts hereinafter 20 described and claimed, and while the invention is not restricted to the exact details of construction disclosed or suggested herein, still for the purpose of illustrating a practical embodiment thereof reference is had to 25 the accompanying drawings, in which like reference characters designate the same parts in the several views, and in which—

Figure 1 shows a front elevation of the supporting rod and parts movably supported thereon;

Fig. 2 is a detail view of one of the traverse rings partly in section showing the construction of the preferred form of my improvement;

Fig. 3 is a face view of the same ring with the cord attachment open;

Fig. 4 is a vertical transverse sectional detail on the line 4—4 of Fig. 2; and

Fig. 5 is a horizontal sectional view on the 45 line 5—5 of Fig. 2.

Referring now more particularly to the drawings, I show by way of illustration of a preferred means for carrying out the invention, a pole 10 supported at its ends as usual 50 in the side posts 11 of an archway. Adjacent the ends of the pole are fixed pulley

rings 12 and 13, the former having two pulleys 14 and 15, while the latter has a single pulley 16.

Remote from the pulley rings are a pair 60 of traverse rings 17, to each of which the traverse cord 18 is adapted to be clamped or anchored in a reliable manner. Between each of the pulley rings and the traverse ring on the same side of the archway are a 65 series of idle supporting rings 19 of any suitable or well known construction. The curtains, portières or the like, indicated at 20, are supported upon or from the rings above described by pins, hooks or the like, 70 indicated at 21.

In the usual practice of traverse cords and rings, the cord is tied around each of the traverse rings which requires special skill on the part of the operator and considerable 75 waste of time in assembling the parts, but when the tying is done by one who is unskilled much trouble ensues because of the slippage of the cord or the failure of the drapery to operate as desired. As shown 80 herein, the traverse cord 18 is threaded over one of the pulleys, say 14, of the ring 12, thence directly through the idle rings 19 and the traverse ring 17 on the same side of the arch, and thence through the adjacent traverse ring where it is clamped and thence it is extended through the remaining 85 idle rings 19 on the opposite side, and thence around the pulley 16 in the opposite fixed pulley 13. The cord is thence extended 90

backwardly through the rings 19 and traverse ring on the same side as the pulley 13, thence to the traverse ring on the first side where it is clamped, and thence it is ex- 95 tended through the idle rings and over the pulley 15 on the first mentioned side, the free ends of the cord being provided with handles or tassels for manipulation. As shown in Fig. 1, a downward pull upon the 100 tassel 22 will cause the traverse ring 17 on the same side to be drawn directly toward the pulley 12 carrying with it the idle rings 19.

At the same time the cord by virtue of the pulley 16 and the connection with the other traverse ring will cause the latter traverse ring to move in the opposite direction, carrying with it the idle rings between it and the ring 13. It will thus be seen that the portières or curtains 20 will be opened quickly and directly, moving from each 105 other. The tassel 23 will move upwardly accordingly toward the ring 12. In order to 110

close the curtains, a downward pull upon the tassel 23 will cause a movement of the traverse rings toward each other, returning the devices promptly and easily to the position shown in Fig. 1.

The traverse ring 17 may be made of any suitable structure or design. I provide a clamping device for the traverse cord of such a nature, however, that the internal 10 diameter of the rings need be very slightly larger than the diameter of the pole 10.

Each traverse ring is formed, as indicated herein, preferably at its bottom side with a depression 24 forming a pit or notch 24' at 15 the deepest place. If the ring be made of sheet metal, this depression and notch may be formed by swaging the metal downwardly or outwardly with respect to the center of the ring. The clamp shown herein comprises a jaw 25 extending into and secured 20 in the depression and pit aforesaid and forming a seat for the cord 18. This fixed jaw may be secured in place by soldering, brazing or by any other suitable positive permanent 25 means. The clamp includes also a movable jaw 26 having integral connection at one end at 27 with the fixed jaw. The material of the clamp is preferably spring metal and the movable jaw may have an inherent 30 tendency to spring upwardly or inwardly away from the fixed jaw, as shown in Fig. 3, but the free end of the movable jaw is adapted to be forced downwardly toward the adjacent end of the fixed jaw and 35 there secured by some simple easily manipulated device, such as a keeper 28, in the form of a ring slidable along the traverse ring. The movable jaw is provided with a protection 40 26' extending into or toward the seat formed in the fixed jaw for the cord for the purpose of increasing the grip on said cord. I also preferably roughen or serrate the gripping surfaces of the jaws so as to make it practically impossible for the cord to slip 45 when it is once secured.

In order to connect the cord to the traverse rings improved as herein described, the curtains are hung upon all of the rings as usual. The cord is then threaded through 50 the pulleys and rings as described, and then with the curtains adjusted as desired along the pole and the cord correspondingly positioned, the operator has but to slip the two portions of the traverse cord into the clamps, 55 each portion of the cord slipping freely beneath the movable jaw 26 when the keeper 28 is spaced therefrom. After the cord is in place, the operator brings the keeper down into frictional engagement with the 60 clamp, as shown in Figs. 2 and 5, and the

operation is completed. Since there is nothing tending to loosen the keeper it is impossible for the cord to slip in either direction through the clamps. Furthermore, practically none of the interior space of the rings 65 is occupied by the clamping device. By this means I provide a much neater, as well as a much more convenient traverse cord attachment than has heretofore been brought to my notice. 70

I claim:

1. The herein described traverse ring having in one side a depression and a pit formed in the center thereof, and a cord clamp having a relatively stationary jaw secured in said depression and having at its center a depression extending into said pit and forming a cord seat, said clamp including a relatively movable jaw having spring connection at one end with the stationary jaw, and means to bind the movable jaw in binding engagement with the cord. 75

2. The combination with a traverse ring, of a traverse cord attachment means co-operating therewith, said attachment means 80 comprising a clamp having relatively fixed and movable jaws formed of a single piece of spring material, the fixed jaw having a seat to receive the cord and the movable jaw having a projection extending into said seat, 85 said seat and projection being provided with serrations, and means serving to hold the free end of the movable jaw in gripping position.

3. The herein described traverse ring having in one side a depression and a pit formed at the center thereof, and a cord clamp having a relatively stationary jaw secured in said depression and having at its center a depression extending into said pit and forming 100 a cord seat, said clamp including a relatively movable jaw having spring connection at one end with the stationary jaw, and means slidable endwise of the clamp to bind the movable jaw in positive binding engagement 105 with the cord.

4. The combination with a traverse ring, of a traverse cord attachment means co-operating therewith, said attachment means 110 comprising a clamp having relatively fixed and movable jaws formed of a single piece of spring material, the fixed jaw having a seat to receive the cord and the movable jaw having a projection extending into said seat, 115 said seat and projection being provided with serrations, and a keeper slidable longitudinally of the clamp to hold the free end of the movable jaw in gripping position.

JOHN A. DONNELLY.
